Primary Examiner — Elizabeth A. Albert(74) *Attorney, Agent, or Firm* — Brooks Kushman P.C.(57) **CLAIM**

The ornamental design for a drawing instrument holder, as shown and described.

DESCRIPTION

FIG. 1 is a front perspective view of a drawing instrument holder showing my new design.

FIG. 2 is a rear perspective view of FIG. 1;

FIG. 3 is a front elevational view of FIG. 1;

FIG. 4 is a rear elevational view of FIG. 1;

FIG. 5 is a side elevational view of FIG. 1; the other side elevational view is a mirror image of this view;

FIG. 6 is a top plan view of FIG. 1; and,

FIG. 7 is a bottom plan view of FIG. 1.

The broken lines in the drawings are included to show features that form no part of the claimed design.

1 Claim, 3 Drawing Sheets(56)
